[57] CLAIM

The ornamental design for a container for lottery tickets, as shown.

DESCRIPTION

FIG. 1 is a top perspective view of a container for lottery tickets showing my new design;

FIG. 2 is a bottom perspective view thereof;

FIG. 3 is a left side elevation thereof;

FIG. 4 is a rear elevation thereof;

FIG. 5 is a front elevation thereof;

FIG. 6 is a bottom plan view thereof;

FIG. 7 is a top perspective view thereof; in an open position;

FIG. 8 is a right side elevation of FIG. 7; the left side elevation being a mirror image; and

FIG. 9 is an elevation of FIG. 7 taken along line 9—9 of FIG. 7.
